[57] ABSTRACT

Interception of light, which is emitted by a light emitter positioned on one vertical side of the warp sheet, by the weft at the moment of picking motion is sensed by a light receiver positioned on the other vertical side of the warp sheet while cutting off luminous noises by the warp sheet and, after the photoelectric conversion, corresponding electric signals are given to a discrimination circuit so that the absence of weft at the time of the picking motion will cause instant interruption of the loom running.

PHOTOELECTRIC TYPE WEFT SENSING PROCESS AND WEFT SENSOR

The present invention relates to a photoelectric type weft sensing process and a weft sensor. More particularly the invention relates to a process for sensing weft during picking motion by light emission across the warp sheets and also to a weft sensor for carrying out such a process on weaving looms.

Even in the conventional art, a mechanism called the center fork has been used in the weaving field in order to sense the absence of the weft and/or incorrect insertion of weft at the time of the picking motion. In the case of this mechanism, sensing of the weft is carried out through direct contact of the fork with the weft under picking. Such direct contact of the fork with the weft tends to damage the weft and to develop undesirable thread loops on the surface of the fabric obtained therefrom. In addition, the fabric surface is liable to be soiled by flying machine oil and damaged by the fork.

A principal object of the present invention is to provide a process and a sensor for carrying the weft sensing work on looms in a photoelectric manner without direct contact of the sensing terminal with the weft under picking.

Another object of the present invention is to provide a process and a sensor for carrying out the photoelectric weft sensing work with increased reliability while eliminating luminous noises caused by warp sheets.

In order to attain these objects, the weft sensing light beams of the present invention are emitted from a light emitter located on one vertical side of the warp sheet(s) at a position about the middle of the lathe length, the light beams so emitted being advanced across the warp sheet(s) and the course of the weft under picking so as to be received by a light receiver located on the other side of the warp sheet(s). The light beams so received are converted into corresponding electric signals by one or more photoelectric cells incorporated within the light receiver by a filtering operation by a weft-image selector mechanism and the electric signals so produced are given to a discrimination circuit. The running of the loom is interrupted only when the absence of the weft at the time of picking motion is sensed.

Further features and advantages of the present invention will be made clearer from the following description, reference being made to the accompanying drawings, in which:

FIG. 1 is a front plane view of a loom equipped with the photoelectric type weft sensor of the present invention;

FIG. 2 is a side plane sectional view of the basic embodiment of the photoelectric type weft sensor of the present invention;

FIG. 3A is a side plane sectional view of the light receiver used in the weft sensor of the present invention and provided with the first embodiment of the weft-image selector mechanism;

FIG. 3B is a bottom plane view of the light receiver shown in FIG. 3A;

FIG. 4 is a bottom plane view of the second embodiment of the weft-image selector mechanism used in the weft sensor of the present invention;

FIG. 5A is a side plane sectional view of the light receiver used in the weft sensor of the present invention

and provided with the third embodiment of the weft-image selector mechanism;

FIG. 5B is a bottom plane view of the light receiver shown in FIG. 5A;

FIG. 6 is a perspective plane view of a typical embodiment of the mechanism for producing synchronizing pulses in the weft sensor of the present invention;

FIG. 7 is a block diagram showing the structure of an embodiment of the discrimination circuit used in the weft sensor of the present invention;

FIGS. 8A and 8B are explanatory top plane views of the lathe and its related arrangement at different moments in the crank cycle;

FIGS. 9A and 9B are graphic drawings showing conversion in the wave-form of signals processed through the discrimination circuit shown in FIG. 7;

FIG. 10 is a perspective plane view of another embodiment of the weft sensor of the present invention and its related loom parts;

FIG. 11 is a vertical cross sectional plane view of the weft sensor shown in FIG. 10;

FIGS. 12A through 12D are explanatory top plane views of several modifications of the weft sensor shown in FIG. 10;

FIGS. 13A and 13B are explanatory views showing two different running fashions of the weft course;

FIGS. 14A and 14B are graphic drawing showing two different production modes of wave-forms indicating the presence of weft;

FIG. 15 is a partly sectional side plane view of still another embodiment of the weft sensor of the present invention;

FIG. 16 is a sectional side plane view of a light receiver used in the weft sensor shown in FIG. 15;

FIG. 17 is a top plane view of the light receiver shown in FIG. 16;

FIG. 18 is a block diagram of one example of the discrimination circuit used in combination with the weft sensor shown in FIGS. 15 through 17;

FIG. 19 is a graphic drawing showing conversion in the wave-form of signals processed through the discrimination circuit shown in FIG. 18;

FIG. 20 is a partly sectional side plane view of a still further embodiment of the weft sensor of the present invention;

FIG. 21 is a sectional front plane view of the weft sensor shown in FIG. 20;

FIG. 22 is a top plane view, partly omitted, of the weft sensor shown in FIG. 20;

FIG. 23 is a perspective plane view of a still further embodiment of the weft sensor of the present invention;

FIG. 24 is a partly sectional side plane view of a modification of the embodiment shown in FIG. 23;

FIG. 25 is a partly sectional top plane view of the main part of the arrangement shown in FIG. 24;

FIGS. 26A and 26B are top explanatory views of the weft sensing operation using the arrangements shown in FIGS. 23, 24 and 25.

The entire structure of a loom equipped with the basic embodiment of the photoelectric type weft sensor of the present invention is shown in FIG. 1 in a somewhat simplified illustration, the structure being basically the same as that of ordinary looms. Briefly mentioning the structure, a tappet shaft 2 and a rocking shaft 3 extending laterally transverse the loom width

and are carried on both sides by side frames 1 of the loom, the rocking shaft 3 carrying lathe swords 4 in a to-and-fro swingable disposition. The lathe swords 4 carry at their top ends a lathe 6, along the upper face of which a shuttle 7 reciprocates for insertion of weft 8. In the drawing, the weft 8 is illustrated by a chain and dot line. This reciprocal movement of the shuttle 7 is effected by pickers 9 disposed to tops of corresponding picking sticks 11 which are mounted on both end parts of the rocking shaft 3 and operated for the picking motion by associated picking bands 12. A reed cap 13 is mounted above the lathe 6 in order to accommodate multiple side-by-side aligned reeds 14 between them. In the disposition illustrated in the drawing, the warp shed is open and warps are divided into two sheets 16a and 16b spacedly sandwiching the course assumed by the weft 8 at the time of the picking motion. By the swing movement of the lathe swords 4, the weft 8 that has been inserted into the warp shed is beaten against the cloth fell 17 of the fabric 18 just under weaving.

Now referring to FIG. 2 also, the weft sensor of the present invention is incorporated in the above-described structure of the loom. A recess 101 is formed in the upper face of the lathe 6 at a position substantially midway of the lathe length. A light emitter 102 is arranged within the recess 101 with its convergent lens 103 facing upwardly. This light emitter 102 is internally provided with a suitable light source such as an electric lamp or a light emitting diode. The light produced by such light source is converged by the lens 103 and, in the form of a beam X, advances towards the lower face of the reed cap 13 across the running path of the shuttle 7. A light receiver 104 is disposed to the lower face of the reed cap 13 at a position where the beam X from the light emitter 102 arrives. This light receiver 104 is provided with a weft-image selector mechanism 106 on its end facing the convergent lens 103 of the light emitter 102. Further, the light receiver 104 is internally provided with a photoelectric cell 107 which is connected to a later described discrimination circuit via electric connections 108.

In a preferred embodiment, a brush 19 is fixed to the breast beam 21 of the loom, projecting rearwardly so that the surface of the lens 103 of the light emitter 102 can be cleaned by the brush 19 at every swinging cycle of the lathe 6. In this connection, however, it should be understood that the provision of such a cleaning brush is quite optional.

The weft-image selector mechanism 106 incorporated in the light receiver 104 has a function of clearly picking up the weft-images in contrast to the warp-images which are always received by the light receiver 104. In other words, for further operation of the weft sensor of the present invention, only the weft-images are selected out of all types of images arriving at the light receiver 104.

The first embodiment of the weft-image selector mechanism is shown in FIGS. 3A and 3B, in which the light receiver 104 includes: a casing 109 having a cavity; the photoelectric cell 107 incorporated within the casing 109; the electric connection 108; and; a bottom lid 111 disposed to the open bottom end of the casing 109. This bottom lid 111 is provided with a long straight slit 112 which runs in the direction of the weft inserting courses 8a and 8b as shown in FIG. 3B. In the present embodiment, the weft-image selector mechanism 106 is in the form of this bottom lid 111 having

the long slit 112. By provision of this straight slit 112, useless images such as the warp-images are effectively shut out and only the necessary weft-images are skillfully picked out with excellent clearness. Dimensions of the slit 112 are determined in accordance with the densities of the threads in the fabric structure. For example, when the warp density amounts to 70 ends/inch and the weft density amounts to 40 picks/inch, the width of the slit 112 is in a range 0.3 through 0.5 mm, and the length thereof is about 10 mm.

The second embodiment of the weft-image selector mechanism is shown in FIG. 4. This embodiment is particularly suited for use on looms of small weaving width. In the case of such looms of small weaving width, the advancing courses assumed by the weft under picking are in general inclined considerably against the direction of the cloth fell. Taking this fact into consideration, the weft-image selector mechanism shown in FIG. 4 has a bottom lid 111 provided with an X-shaped slit 113. This shape of the slit 113 meets the crossed courses 8a and 8b which are assumed by the weft 8 at the time of picking motion, i.e. the courses considerably inclined against the cloth fell.

The third embodiment of the weft-image selector mechanism of the present invention is shown in FIGS. 5A and 5B. In the case of this embodiment, the weft-image selector mechanism is in the form of a bottom lid 111 disposed to the open bottom end of the casing 109 and a column-shaped convex lens 114 incorporated in the bottom lid 111. As shown in FIG. 5B, the convex lens 114 is elongated in the direction of the weft courses 8a and 8b at the time of the picking motion. Due to the convexity of the lens 114, the image of the weft arrives at the photoelectric cell 107 in an enlarged state. When a long distance is needed for this optical enlargement, the light receiver 104 may advantageously be so structured that the course of the beam after passing through the lens 114 can be properly refracted.

In the actual use of the photoelectric type weft sensor of the present invention, the sensing operation is carried out at a moment in the loom crank cycle close to the top dead center position. That is, when the top dead center is taken as the starting position of the loom crank cycle, the sensing operation takes place in a region of 350 through 35° of the crank angle. This period corresponds to the time when the lathe is positioned around the middle of its swinging stroke. At this very moment, the warp shed is closed as shown in FIG. 2, the weft 8 is caught by the warp sheets 16a and 16b, and the movement of the weft towards the cloth fell 17 is considerably lowered, which disposition is suited to the sensing operation of weft breakages. Separately from the above-described arrangement, suitable synchronizing pulses are produced at a moment corresponding to the top dead center of the crank cycle and are given to the later-described discrimination circuit also.

One typical embodiment of the mechanism for producing such synchronizing pulses is illustrated in FIGS. 6, 1 and 6, in which a circular disc 116 or a like member is fixedly mounted on the tappet shaft 2 and is provided with a window 117 extending therethrough. A light source element 119 carried on a common arm 118 is positioned on one side of the disc 116 and a photoelectric cell element 121 is on the other side thereof. The relative arrangement of the window 117 and the elements 119 and 121 is so designed that the window 117

traverses the light beam emitted from the element 119 at a moment corresponding to the top dead center of the crank cycle. In other words, at every moment of the crank cycle top dead center, the light from the light source element 119 is received by the photoelectric cell element 121 so as to produce corresponding synchronizing pulses, which are given to the above-described discrimination circuit via electric connections. The arm 118 is fixed to a suitable stationary part of the loom framework.

One typical embodiment of the above-mentioned discrimination circuit is illustrated in FIG. 7, in which the photoelectric cell 107 of the light receiver 104 (see FIG. 2) is connected to a gate circuit 124 via an amplifier circuit 123. This gate circuit 124 is connected to a flip-flop circuit 129 via a shaping circuit 126, a differentiation circuit 127 and a rectifier circuit 128. Separately from this, the photoelectric cell element 121 of the synchronizing pulse producing mechanism is connected to a shaping circuit 132 via an amplifier circuit 131. The output terminal of the shaping circuit 132 is firstly connected to the input terminal of the gate circuit 124. The output terminal of the shaping circuit 132 is secondly connected to a rectifier circuit 136 via an inverter circuit 133 and a differentiation circuit 134. The output terminal of the rectifier circuit 136 is also connected to the input terminal of the flip-flop circuit 129. The output terminal of the shaping circuit 132 is thirdly connected to an inverter circuit 141 via a differentiation circuit 137, a rectifier circuit 138 and a one-shot-multi-vibrator circuit 139. The output terminals of the flip-flop circuit 129 and the inverter circuit 141 are both connected to input terminals of a NOR circuit 142, which is further connected to an operation terminal 144 via a relay circuit 143. In the present case, the operation terminal 144 is in the form of a mechanism for stopping the running of the loom. In the illustration, signals transmitted from element to element are designated with alphabetic letters. Although detailed structures are not specifically shown in the drawing, the component circuits of the discrimination circuit are of conventional types which are generally known to persons skilled in the art. For example, the differentiation circuits are given in the form of the so-called RC circuits of proper time constant RC.

The photoelectric type weft sensor of the present invention having the above-explained structure operates in the following fashion.

When the warp shed is open, the shuttle 7 flies along the upper face of the lathe 6 from a shuttle box on one side of the loom towards a shuttle box on the other side of the loom. The lathe 6 assumes the disposition shown in FIG. 8A around the time when the shuttle is received in the shuttle box on the receiving side. In this disposition, the weft assumes one of the courses 8a or 8b shown with chain-and-dot lines in the drawing and, in either case, the course is inclined against the cloth fell 17. About the time corresponding to the vicinity of the top dead center of the crank cycle, the lathe 6 assumes the disposition shown in FIG. 8B and the warp shed is closed so that the inserted weft 8 will be caught by the warp sheets 16a and 16b as shown in FIG. 2. In this disposition, the weft course 8a or 8b runs across a zone right under the weft-image selector mechanism 106 of the light receiver 104.

When the weft 8 runs across this zone, the light emitted from the light emitter 102 is temporarily inter-

cepted by the weft 8 and the intensity of the light arriving at the photoelectric cell 107 through the weft-image selector mechanism 106 is accordingly reduced. This presence of the weft 8 can be very successfully sensed by the weft sensor of the present invention due to the excellent weft-image pick-up function possessed by the weft-image selector mechanism 106. This sensing can be accomplished regardless of the disturbance caused by the constant presence of the warp sheets.

10 The process of fashioning electric pulse signals in the discrimination circuit will now be explained in detail with reference to FIGS. 7, 9A and 9B. In FIGS. 9A and 9B, the abscissa designated two full revolutions of the loom crank. The wave-form A shows the output signal from the light receiver 104. The wave-form A includes a negative pulse *a* when the presence of the weft 8 is sensed. In case the weft 8 is absent at the very moment of the weft sensing, the wave-form A does not include such a pulse. This situation is seen in the second revolution of the loom crank. At the time of the beating motion, the light emitter 102 incorporated in the lathe 6 comes under the fabric 18, i.e. the intensity of the light arriving at the light receiver 104, is temporarily reduced and this produces another negative pulse *b* on the wave-form A. Passage of the shuttle 7 produces still another negative pulse *c* on the wave-form A. It will be well understood that the two types of negative pulses *b* and *c* appear periodically once in every revolution of the loom crank. After amplification by the amplifier circuit 123, the wave-form A, including such three types of negative pulses *a*, *b* and *c*, is applied to the gate circuit 124.

35 Separately from this procedure, the synchronizing pulses produced periodically by the above-mentioned synchronizing pulse producing mechanism, e.g., the one shown in FIG. 6, are applied to the shaping circuit 132 after amplification by the amplifier circuit 131. The output wave-form F from the shaping circuit 132 is then applied to the gate circuit 124. Due to the gating operation by the gate circuit 124, the output wave-form B from the gate circuit 124 includes only pulses corresponding to the negative pulses *a* possessed by the wave-form A. By further passing through the shaping circuit 126, the differentiation circuit 127 and the rectifier circuit 128, the wave-form B is converted into the wave-form C, the wave-form D and finally into the wave-form E, which is applied to the flip-flop circuit 129 for the re-setting purpose.

50 The output wave-form F of the shaping circuit 132 is applied to the inverter circuit 133 and converted into the wave-form G, which is converted into the wave-form J and the wave-form K by being processed through the differentiation circuit 134 and the rectifier circuit 136. This wave-form K contains negative pulses *k* which slightly precede the negative pulse(s) *a* of the wave-form A. The wave-form K of this shape is applied to the flip-flop circuit 129 for the setting purpose.

60 The output wave-form F of the shaping circuit 132 is further applied to the differentiation circuit 137, and converted into the wave-form H, the wave-form I, the wave-form N and finally into the wave-form O by being processed through the rectifier circuit 138, the one-shot-multi-vibrator circuit 139 and the inverter circuit 141. This output wave-form O of the inverter circuit 141 is applied to the NOR circuit 142. Between the two output wave-forms L and M, only the wave-form

M, having a negative pulse m , is applied to the NOR circuit 142.

As already described, the presence of the negative pulse a in the wave-form A results in the corresponding presence of a pulse e in the wave-form E which is applied to the flip-flop circuit 129 and, due to the presence of this pulse e , the flip-flop circuit 129 is reset. In other words, when the presence of the weft is sensed, the flip-flop circuit 129 is reset accordingly. By this resetting of the flip-flop circuit 129, the pulse m of the wave-form M disappears and the output wave-form P of the NOR circuit 142 becomes nil. Accordingly, the relay circuit 143 and the operation terminal 144 do not function and the loom continues running. This procedure is seen in the first revolution of the crank cycle shown in FIG. 9B.

On the other hand, when the weft 8 is absent at the moment of the weft sensing, no negative pulse is produced on the wave-form A as shown in the second revolution of the crank cycle in FIG. 9A. Accordingly, the output wave-form E of the rectifier circuit 128 possesses no resetting pulse e so that the flip-flop circuit 129 is not reset at this time. Due to the flip-flop circuit 129 not being reset, the output wave-form M of the flip-flop circuit 129 is superimposed with the output wave-form O of the inverter 141 and the NOR circuit 142 accordingly produces the output wave-form P having a pulse p as shown in the second revolution of the crank cycle in FIG. 9B. This output wave-form P energizes the relay circuit 143 so that the latter produces the wave-form Q. This wave-form Q is applied to the operation terminal 144 and the output wave-form R thereof causes interruption of the loom running.

Although the light emitter is incorporated in the lathe surface and the light receiver is disposed to the lower side face of the reed cap in the foregoing embodiments, their arrangement may be reversed when required. It is also possible to dispose both of these elements to a common loom part on one side of the warp line and to provide a suitable light reflective member on the other side of the warp line. In this case, the weft sensing light beam emitted from one member goes through the warp sheets, reflected on the other side of the warp line, comes back through the warp sheets and is received by the other member.

Another embodiment of the weft sensor of the present invention having a modification in the structure of the light receiver is shown in FIG. 10. In this embodiment a light emitter 202 is disposed to the front face of the reed cap 13 with its light emitting side being directed downwards. Facing this, a light receiver 204 is incorporated in the upper face of the lathe 6.

As shown in FIG. 11, the light receiver 204 includes a cavitated casing 209 and an upper lid 212 disposed to the upper end of the former. In the upper end part, the casing 209 is provided with three sets of separate cavities 213a, 213b and 213c. At locations corresponding to the cavities, the upper lid 211 is provided with windows 212a, 212b and 212c, whose arrangement is described later in detail. In each cavity, a photoelectric cell 207a or 207b or 207c is incorporated and the three photoelectric cells are connected in series to each other by an electric connection 208 which is connected to the discrimination circuit. It will be well understood that, in the case of this embodiment, the weft-image selector mechanism is in the form of the upper lid 211

provided with a plurality of windows 212a, 212b and so on.

Several embodiments of the arrangement of the windows formed in the upper lid 211 are shown in FIGS. 12A to 12D. In every case, the windows are in the form of long slits whose longitudinal direction cross the warp direction and whose widths slightly exceed the weft diameter.

The upper lid 211 shown in FIG. 12A is provided with three windows among which the left-side window 212a runs below and substantially parallel to the running course 8a of the weft which is picked from left to right. The right-side window 212c runs below and substantially parallel to the running course 8b of the weft which is picked from right to left. The middle window 212b runs below the crossing point P of the two weft running courses and substantially parallel to the cloth fell 17.

In the embodiment shown in FIG. 12B, both side windows 212a and 212c are located on a similar side of the middle window 212b. The directions of the side windows 212a and 212c meet the running courses 8a and 8b of the picked weft and the middle window 212b includes the crossing point P in the above-described sense.

In the case of the embodiment shown in FIG. 12C, the upper lid 211 is provided with five windows. The location of the middle window 212b is the same as those in the preceding embodiments, i.e. the crossing point P falls within the area of the middle window 212b. On the left side of the middle window 212b, two side windows are formed, one of which 212a meets the left-to-right weft course 8a and the other of which follows the right-to-left weft course 8b. Similarly on the right side of the middle window, one window 212d catches the left-to-right weft course 8a and the other window 212e the right-to-left weft course 8b.

The upper lid 211 shown in FIG. 12D has three windows. The middle window 212b includes the crossing point P as in the preceding cases. The left side window 212a in this embodiment runs substantially parallel to the cloth fell 17 and is obliquely crossed by the left-to-right weft course 8a. The right side window is substantially parallel to the cloth fell 17 and is obliquely crossed by the right-to-left running course 8b of the weft in the picking motion.

Sensing of weft, using the above-described embodiments of the weft-image selector mechanism, is carried out in the following fashion. Reference is made to the embodiment shown in FIG. 12A only for a clear understanding.

In the case shown in FIG. 13A, the weft assumes a left-to-right course 8a which locally crosses the two windows 212a and 212b. By this local crossing of the respective window by the weft, a relatively small wave-form F_1 is produced by, e.g., the photoelectric cell 207a of the window 212a as shown in FIG. 14A. The size of the wave-form so produced is dependent upon the local length of the weft crossing the window. In the illustrated example, such a wave-form is also produced by the photoelectric cell 207b of the middle window 212b. Because the photoelectric cells of the respective windows are electrically connected in series to each other, the wave-forms produced by the respective photoelectric cells are added to produce a total wave-form F_2 in FIG. 14A and this total wave-form F_2 is brought into the discrimination circuit. In this case, the discrimina-

tion circuit is so designed that wave-forms of the size F_2 or larger can be picked up as they are separated from luminous noises. Under some situations, the weft course $8a$ may not cross the left side window $212a$ at all, but fully cross the middle window $212b$. In this case also, if the produced total wave-form is equal to the wave-form F_2 or larger, the discrimination circuit picks up such wave-form and, as already explained, the running of the loom continues.

In the situation shown in FIG. 13B, both windows $212a$ and $212b$ are fully crossed by the left-to-right weft course $8a$. As the produced total wave-form F_3 is clearly larger than the wave-form F_2 , the running of the loom naturally continues.

Absence of the weft at the time of the weft sensing causes no production of the wave-form or forms so that, by the above-explained function of the discrimination circuit, the running of the loom is instantly interrupted. In this way, the presence of the weft at the time of the weft sensing is sensed with few failures and, accordingly, the unnecessary and misoperated interruption of the loom running can be remarkably reduced.

Still another embodiment of the weft sensor of the present invention is shown in FIGS. 15 through 17. In these figures a light emitter 302 is disposed to the front face of the reed cap 13 , and a light receiver 304 is incorporated in the lathe 6 confronting the light emitter 302 . As shown in FIG. 16, the light receiver 304 includes an internally cavitated casing 309 and an upper lid 311 disposed to the upper end of the casing. In the upper end part, the casing 309 is provided with two cavities $313a$ and $313b$ separated from each other, the cavity $313a$ being on the side of the reed 14 and the cavity $313b$ being on the side of the cloth fell 17 . (see FIG. 15)

The cavities $313a$ and $313b$ are internally provided with photoelectric cells $307a$ and $307b$, respectively, which are connected to a later described discrimination circuit via electric connections $308a$ and $308b$.

At positions corresponding to the cavities of the casing 309 , the upper lid 311 is provided with two windows $312a$ and $312b$, respectively. It will be well understood that, when the lid 311 is disposed to the casing 309 , the window $312a$ positions near the reeds 14 while the window $312b$ positions are remote from the reeds 14 , i.e., on the side of the cloth fell 17 of the fabric 18 . (see FIG. 15) As shown in FIG. 17, the reeds side window $312a$ is in the form of a relatively narrow slit elongated in the weft picking direction. This window $312a$ serves to pick up the weft-image out of luminous noises caused by warp-images. The other window $312b$ on the cloth fell side is in the form of a relatively wide slit which runs substantially parallel to the first mentioned reeds side window $312a$. The photoelectric cell $307b$ on the back side of the window $312b$ is not influenced by the images of the weft and warps.

One example of the discrimination circuit used in the above-described weft sensor mechanism is shown in FIG. 18, in which the photoelectric cell $307a$ in FIG. 16 is connected to a discriminator 316 via an amplifier circuit 314 . The discriminator 316 is further connected to a flip-flop circuit 321 via an integration circuit 317 , a discriminator 318 and a differential rectifier circuit 319 . The output of the first named discriminator 316 is connected to the input terminal of the flip-flop circuit 321 via a gate circuit 322 .

On the other hand, the photoelectric cell $307b$ of the light receiver 304 is connected to a differential rectifier circuit 327 via an amplifier circuit 323 and a discriminator 324 . The output terminal of the discriminator 324 is connected to the input terminal of the gate circuit 322 also via an inverter circuit 326 .

The output terminals of the flip-flop circuit 321 and of the differential rectifier circuit 327 are connected to a common AND circuit 328 , whose output is further connected to an operational terminal 329 , such as the one 144 shown in FIG. 7.

Using the above-described electric arrangement in combination with the mechanical arrangement shown in FIGS. 15 to 17, the weft sensing work is carried out in the following manner. The processing mode of the wave-form signals through the discrimination circuit of FIG. 18 is graphically shown in FIG. 19, in which one and a part of the following revolutions of the loom crank cycle are illustrated.

At the moment when the weft sensor and its related loom parts assume the disposition shown with chain-and-dot lines in FIG. 15, a correctly inserted weft 8 would be placed just under the light emitter 302 of the weft sensor. This presence of the weft intercepts the light running from the emitter 302 to the receiver 304 . Interception of the light is caused by the fabric portion near the cloth fell 17 also. Interception of the light by the weft 8 produces weft pulses a'_w and b'_w in output wave-forms A' and B' from the photoelectric cells $307a$ and $307b$, respectively. Concurrently, interruption of the light by the fabric 18 causes the production of corresponding fabric pulses a'_f and b'_f in output wave-forms A' and B' also. (see FIG. 19)

When the presence of the weft 8 is sensed at the time of the weft sensing, production of the weft pulse b'_w in the wave-form B' slightly precedes that of the weft pulse a'_w in the wave-form A' . This is because, as shown in FIG. 17, the window $312b$, i.e., the photoelectric cell $307b$, is nearer the cloth fell 17 than the photoelectric cell $307a$. Following the production of the weft pulses a'_w and b'_w , the fabric pulses a'_f and b'_f are developed on the respective wave-forms A' and B' . Because the front side window $312b$ is larger than the rear side window $312a$, its corresponding weft pulse b'_w is not so intensive as the weft pulse a'_w of the rear side window $312a$. Further, because the photoelectric cell $307b$ is located nearer the cloth fell 17 than the photoelectric cell $307a$, the fabric pulse b'_f of the front side window $312b$ lasts longer than the fabric pulse a'_f of the rear side window $312a$.

The output wave-form B' of the front side photoelectric cell $307b$ is brought into the discriminator 324 after amplification by the amplifier circuit 323 , and the discrimination is carried out at a prescribed level in the discriminator 324 . The output wave-form C' of the discriminator 324 is applied on one hand to the inverter circuit 326 and on the other hand to the differential rectifier circuit 327 . The output wave-form C' of the discriminator 324 includes fabric pulses c'_f only.

Concurrently with this procedure, the output wave-form A' of the rear side photoelectric cell $307a$ is applied to the discriminator 316 after being amplified by the amplifier circuit 314 , and the discrimination is carried out at a prescribed level in the discriminator 316 . The output wave-form D' of the discriminator 316 is applied on one hand to the integration circuit 317 and on the other hand to the gate circuit 322 . This output

wave-form D' of the discriminator 316 includes weft pulses d'_w and fabric pulses d'_F .

The output wave-form C' is applied to a wave-form inv. C' by the inverter circuit 326, and this wave-form inv. C' is applied to the gate circuit 322. By this introduction of the wave-form inv. C' , the gate circuit 322 is cut off for periods corresponding to the fabric pulses c'_F possessed by the wave-form inv. C' . As already explained, the gate circuit 322 is receptive to the output wave-form D' from the discriminator 316. Here, due to the cut-off work by the wave-form inv. C' from the inverter circuit 326, the fabric pulses d'_F possessed by the wave-form D' are cut-off. Also, an output wave-form E' of the gate circuit 322 includes a pulse e'_w only, which corresponds to the weft pulse d'_w possessed by the wave-form D' . This output wave-form E' is then fed to the flip-flop circuit 321 for a setting purpose.

The output wave-form D' of the discriminator 316 is bypassed and also applied to the integration circuit 317. The output wave-form F' of the integration circuit 317 includes a weft pulse f'_w corresponding to the weft pulse d'_w of the wave-form D' , and fabric pulses f'_F corresponding to the fabric pulses d'_F .

This output wave-form F' is then fed to the discriminator 318 and the differential rectifier circuit 319, whose output wave-form H' is applied to the flip-flop circuit 321 for a resetting purpose. An output wave-form I' of the flip-flop circuit 321 is fed to the AND circuit 328 which is receptive to the output wave-form J' of the differential rectifier circuit 327.

When the zero valued portion i' of the wave-form I' meets the pulse of the wave-form J' , no pulse is formed on an output wave-form K' of the AND circuit 328, the operation terminal 329 is not excited by the output wave-form K' and the loom carries on its running. In other words, the presence of the weft at the moment of the weft sensing causes no interruption of the loom running. This has taken place in the first revolution of the loom crank cycle shown in FIG. 19.

In case the weft 8 is not sensed at the time of the weft sensing period, i.e., the weft has not been correctly inserted in the shed, the output wave-forms A' and B' of the photoelectric cells 307a and 307b possess no weft pulses as shown in the second revolution of the loom crank cycle (see FIG. 19). In this case, the output wave-form I' of the flip-flop circuit 321 has no zero valued portion and, accordingly, the output wave-form K' of the AND circuit 328 includes a control pulse k' , which excites the operation terminal 329 in order to stop the loom running.

It will be well understood that various modifications may be derived from the above-described basic structure of the weft sensor. For example, if accompanied with a suitable rearrangement of the discrimination circuit, the position of the light receiver 304 in FIG. 15 may be somewhat changed nearer to the reeds 14.

A still further embodiment of the weft sensor of the present invention is shown in FIGS. 20 through 22. In these figures a light emitter 402 is disposed to the front face of the reed cap 13, and a light receiver 404 is incorporated within the lathe 6.

The light receiver 404 includes: a cavitated casing 409 having an internal cavity 413; an upper lid 411 closing the upper open end of the casing 409 and having a window 412 formed therethrough; a photoelectric cell 407 disposed in the cavity 413, and; electric connections 408 connecting the cell to a given discrimination cir-

cuit (not shown). As shown in FIG. 22, the window 412 is in the form of a slit running in the weft direction.

The light emitter 402 includes a cylindrical casing 414 and a cap 416 inserted over the former from the upper side. Within the cavity formed by these members, an electric insulation layer 417 is disposed toward the inner face of the cap 416 and a pair of holder arms 418 is fixed to the inner face of the cap 416 via this insulation layer 417. The holder arms 418 are connected to a given electric source (not shown) by electric connections 419 running through the insulation layer 417 and the cap 416. The pair of holder arms 418 carry a lamp 421 horizontally between them, the lamp 421 having a linear filament 422. Registration of the position of the cap 416 with respect to the casing 414 is so selected that the running direction of the lamp filament 422 is substantially at right angles against the warp direction, i.e., substantially parallel to the weft direction. After registration, both members 414 and 416 are fixed to each other by a suitable set screw 423. A convex lens 424 is disposed to the open bottom end of the casing 414.

Weft sensing is carried out using the left sensor of the above-described structure in the mode explained below.

As shown in FIGS. 20 and 21, the light emitted from the lamp 422 is formed into light beams X by the convex lens 424. Because the filament 422 runs in the weft direction as already explained, the plane illuminated by the light beams X is in the form of a rectangle elongated in the weft direction. Therefore, when seen in the weft direction as in FIG. 20, the light beams X run parallel to each other but at right angles to the upper face of the light receiver 404. When seen in the warp direction as in FIG. 21, some of the light beams X run perpendicular to the upper face of the light receiver 404, while other light beams X run obliquely to the upper face of the light receiver 404. The warp image formed by the straight running light beams is diluted by the oblique running light beams and no clear warp images are formed on the light receiver 404. When the light beams X are intercepted by the weft 8 at the time of the weft sensing, the weft-image is clearly caught by the light receiver 404 as shown in FIG. 21. It will be well understood that, because the axis of the lamp 422 runs substantially perpendicular to the warp direction, i.e. in the weft direction, the luminous noises caused by the presence of the warps can be effectively reduced and the weft-image can be caught with a sufficient intensity.

Further embodiments of the weft sensor of the present invention are shown in FIGS. 23 through 26B, in which light receivers of periodically movable types are employed.

In the embodiment shown in FIG. 23, a light emitter 502 is disposed to the front face of the reed cap 13, and a light receiver 504 is incorporated in a recess 501 formed in the upper face of the lathe 6 at the middle of the same confronting the light emitter 502. In this case, the light receiver 504 is associated with a mechanism 503 for actuating the periodic forward and backward movement thereof.

This actuating mechanism 503 includes a U-shaped lever 506 which carries the light receiver 504 at its upper end and a rotatable roller 507 at its lower end. This lever 506 is pivoted at its lower apex to a shaft 508 carried by a bracket 509 fixed at its upper end to the

front face of the lathe 6. In combination with this, a plate cam 511 is fixed to the rear face of the breast beam 21 extending towards the lathe 6 and passing underneath the roller 507 of the U-shaped lever 506. The U-shaped lever 506 is always urged by a spring 512, which is connected at its one end to the lathe 6 and at its other end to the stem of the lever 506, so that the roller 507 is always placed in pressure contact with the upper face of the plate cam 511.

The plate cam 511 is provided with a shoulder 511a in such a manner that the roller 507 is positioned at the lower side end of the shoulder at a crank angle of about 330°, taking the top dead center as 0°, while it is positioned at the higher side end of the shoulder at a crank angle of about 355°.

The weft sensor having the above-described structure operates in the following manner. The disposition at a crank angle of approximately 330°, taking the top dead center as the starting point of the crank cycle, is shown in FIG. 26A. In this disposition, the course assumed by the weft 8 runs on the front side of the light receiver 504 which rests in the recess 501 of the lathe 6 at this moment. The distance L_w of the weft 8 from the face plane of the reeds 14 in this disposition is greater than the distance L'_w of the light receptive slit of the light receiver 504 in the same sense.

At this exact moment, the light receiver 504 is switched on so as to have the weft sensing faculty and the roller 507 of the actuating mechanism 503 in FIG. 23 approaches the shoulder 511a of the plate cam 511. Following this movement of the roller 507 along the plate cam 511, the light receiver 504 leaves the recess 501; moves towards the cloth fell 17; passes down side of the weft 8, while performing the sensing work; rounds the crank angle of 355°, and; arrives at the position shown in FIG. 26B. In this disposition, the distance L'_w of the weft 8 from the front face of the reeds 14 is smaller than the distance L'_w of the light receptive slit of the light receiver 504 from the front of said reeds 14. The light receptive slit of the light receiver 504 is now positioned very close to the cloth fell 17 of the fabric 18 and, at this moment, the light receiver 504 is switched off so as to lose its weft sensing faculty.

After the beating motion, the lathe 6 recedes with the roller 507 of the actuating mechanism 503 travelling along the plate cam 511 in FIG. 23. After the roller 407 has passed the shoulder 511a of the plate cam 511, the light receiver 504 resumes its resting position within the recess 501 of the lathe 6 as shown in FIG. 26A.

It is clear that, when the weft 8 is not inserted correctly, the light receiver 504 does not catch the weft-image as its passes below the weft course and, accordingly, the running of the loom is interrupted for repair work.

At the time of the cop change, the weft assumes a course 8c which is closer to the reeds 14 than is the normal weft course. However, even in this case, the position of the light respective slit of the light receiver 504 in the rest position (see FIG. 26A) is located closer to the reeds 14 than is this weft course 8c. Therefore, weft sensing can be successfully carried by the light receiver 504 which travels from this rest position to the advanced position shown in FIG. 26B during the period when the crank angle is from 330 through 355°.

A modification of the above-described embodiment is shown in FIGS. 24 and 25. In this embodiment, a recess 516 is formed in the upper face of the lathe 6, and

a pair of U-shaped rails 517 are disposed horizontally to both side ends of the recess 516. A slider plate 518 is inserted between the rails 517 with both its ends being guided by the elongated recesses of the U-shaped rails 517. As seen in the drawings, the slider 518 is movable forwardly and rearwardly in the recess 516 of the lathe 6. This slider 518 is accompanied with the light receiver 504 fixed on its upper surface and also with a rack 519 fixed to the bottom surface thereof.

The above-described assembly is mechanically connected to an actuating mechanism 521, which includes a sector pinion 522 in a meshing arrangement with the above-mentioned rack 519. This pinion 522 is placed in a lower cut-out of the lathe 6 and carried turnably by a shaft part of a bracket 523 fixed to the lower side of the lathe 6.

Separately from this arrangement, an actuator cam 524 is mounted firmly on the tapper shaft 2. A two arm lever 526 is pivotally mounted at its apex to a certain stationary part of the loom. One arm 526a of the lever 526 carries a cam follower roll 527 at its free end while the other arm 526b of the lever 526 is accompanied with a tension spring 528 disposed to the stem thereof. Due to the provision of the spring 528, the roll 527 is always placed in peripheral pressure contact with the cam 524. The free end of the arm 526b is linked to the sector pinion 522 by a rod 529.

In connection with this structure, it will be well understood that the raised surface portion of the actuator cam 524 corresponds to the shoulder 511a of the plate cam 511 in the embodiment shown in FIG. 23. Accordingly, the profile of the actuator cam 524 is so designed that, as in the case of the embodiment shown in FIGS. 23, 26A and 26B, the sensing work of the weft is carried out during the period when the crank angle is from 330 through 355°.

Because the light receiver 504 travels across and below the weft course during the period when the inserted weft is still in a tensed condition, weft sensing can be carried out very successfully without being disturbed by waved, twisted or curled courses of the weft.

What is claimed is:

1. Photoelectric type weft sensing process on weaving looms comprising emitting light beams for sensing weft from one vertical side of a plurality of warp sheets forming a warp shed at a position about the middle of the lathe length in such a manner that said light beams advance across the course of the weft under picking, receiving said light beams on the other vertical side of the warp shed so that weft-images are clearly detected from an image caused by interruption of said light beam by said warp shed, converting photoelectrically said light beams so received into corresponding electric signals, subjecting said electric signals so obtained to an electric discrimination for identifying whether said weft exists or not at the time of a picking motion and interrupting the running of the loom only when said electric signals indicate the absence of weft at the time of picking motion.

2. Photoelectric type weft sensing process as claimed in claim 1 wherein said light beams advance from upper side to underside of said warp shed.

3. Photoelectric type weft sensing process as claimed in claim 1 wherein said light beams advance from under side to upper side of said warp shed.

4. Photoelectric type weft sensor comprising, in combination, a light emitter located on one vertical side of a plurality of warp sheets forming a warp shed at a position about the middle of the lathe length with its light emitting and confronting the warp shed, a light receiver located on the other vertical side of said warp shed with its light receptive and confronting said light emitting end of said light emitter, at least one photoelectric cell incorporated within said light receiver, a weft-image selector mechanism incorporated in said light receiver for clearly separating weft-images from luminous images caused by said warp shed, a discrimination circuit for identifying whether said weft exists or not at the time of a picking motion electrically connected to said light receiver and an operation terminal forming a part of said discrimination circuit for interrupting the running of the loom when the absence of weft at the time of picking motion is sensed.

5. Photoelectric type weft sensor as claimed in claim 4 wherein said light emitter is disposed in said lathe, said light receiver is disposed in the reed cap of the loom, said light receiver includes a cavitated casing and said weft-image selector includes a lid disposed to the light receptive side end of said casing and having one light passable window formed therethrough.

6. Photoelectric type weft sensor as claimed in claim 5 wherein said window is in the form of a straight slit running in the weft direction.

7. Photoelectric type weft sensor as claimed in claim 5 wherein said window is in the form of an X-shaped slit, each branch of which is parallel to one of the directions that wefts are inserted.

8. Photoelectric type weft sensor as claimed in claim 5 wherein said discrimination circuit includes a gate circuit connected to said light receiver, a shaping circuit connected to said gate circuit, a differentiation circuit connected to said shaping circuit, a rectifier circuit connected to said differentiation circuit, a shaping circuit connected to a synchronizing pulse producing mechanism, a rectifier circuit connected to said shaping circuit via an inverter circuit and a differentiation circuit, a flip-flop circuit connected to said rectifier circuits, an inverter circuit connected to said shaping circuit via a differentiation circuit, a rectifier circuit and a one-shot-multi-vibrator circuit, a NOR circuit connected to said flip-flop circuit and to said inverter circuit and said operation terminal connected to the NOR circuit via a relay circuit.

9. Photoelectric type weft sensor as claimed in claim 4 wherein said light emitter is disposed in the reed cap, said light receiver is disposed in said lathe of the loom, said light receiver includes a cavitated casing and said weft-image selector includes a lid disposed to the light receptive side end of said casing and having one light passable window formed therethrough.

10. Photoelectric type weft sensor as claimed in claim 9 wherein said window is in the form of a straight slit running in the weft direction.

11. Photoelectric type weft sensor as claimed in claim 9 wherein said window is in the form of an X-shaped slit, every branch of which is parallel to one of the directions that wefts are inserted.

12. Photoelectric type weft sensor as claimed in claim 9 wherein said discrimination circuit includes a gate circuit connected to said light receiver, a shaping circuit connected to said gate circuit, a differentiation circuit connected to said shaping circuit, a rectifier cir-

cuit connected to said differentiation circuit, a shaping circuit connected to a synchronizing pulse producing mechanism, a rectifier circuit connected to said shaping circuit via an inverter circuit and a differentiation circuit, a flip-flop circuit connected to said rectifier circuits, an inverter circuit connected to said shaping circuit via a differentiation circuit, a rectifier circuit and a one-shot-multi-vibrator circuit, a NOR circuit connected to said flip-flop circuit and to said inverter circuit and said operation terminal connected to the NOR circuit via a relay circuit.

13. Photoelectric type weft sensor as claimed in claim 4 for sensing wefts having a number of inserting courses defined by a trace of weft connecting a selvage of cloth to a shuttle running through an opened shed along the shuttle lathe, wherein said light emitter is disposed in said lathe, said light receiver is disposed in the reed cap of the loom, said light receiver includes a cavitated casing and said weft-image selector mechanism includes a lid disposed to the light receptive side end of said casing and having at least three light passable windows.

14. Photoelectric type weft sensor as claimed in claim 13 wherein said lid includes three windows, one window of which meets the crossing point of two weft inserting courses and the remaining two of which are located on both sides of the first mentioned one and run parallel to the respective weft inserting courses.

15. Photoelectric type weft sensor as claimed in claim 13 wherein said lid includes three windows, one window of which meets the crossing point of two weft inserting courses and the remaining two windows being located on both sides of the first mentioned window and running at at least partly including respective weft inserting courses.

16. Photoelectric type weft sensor as claimed in claim 13 wherein said lid includes three windows, one window of which meets the crossing point of two weft inserting courses and the remaining two of which are located on one common side of the first mentioned one and run parallel to the respective weft courses.

17. Photoelectric type weft sensor as claimed in claim 13 wherein said lid includes five windows, one window of which meets the crossing point of two weft inserting courses, the other two of which are located on one common side of the first mentioned one running parallel to respective weft courses and the remaining two of which are located on the other common side of the first mentioned one running parallel to respective weft courses.

18. Photoelectric type weft sensor as claimed in claim 4 for sensing wefts having a number of inserting courses defined by a trace of weft connecting a selvage of cloth to a shuttle running through an open shed along the shuttle lathe wherein said light receiver is disposed in said lathe, said light emitter is disposed in the reed cap of the loom, said light receiver includes a cavitated casing and said weft-image selector mechanism includes a lid disposed to the light receptive side end of said casing and having at least three light passable windows.

19. Photoelectric type weft sensor as claimed in claim 18 wherein said lid includes three windows, one window of which meets the crossing point of two weft inserting course and the remaining two windows being located on both sides of the first mentioned window

and running parallel to respective weft inserting courses.

20. Photoelectric type weft sensor as claimed in claim 18 wherein said lid includes three windows, one window of which meets the crossing point of two weft inserting courses and the remaining two of which are located on both sides of the first mentioned window and run at least partly including respective weft inserting courses.

21. Photoelectric type weft sensor as claimed in claim 18 wherein said lid includes three windows, one window of which meets the crossing point of two weft inserting courses and the remaining two of which are located on one common side of the first mentioned one and run parallel to respective weft courses.

22. Photoelectric type weft sensor as claimed in claim 18 wherein said lid includes five windows, one window of which meets the crossing point of two weft inserting courses, the other two of which are located on one common side of the first mentioned one running parallel to respective weft courses and the remaining two of which are located on the other common side of the first mentioned window running parallel to respective weft courses.

23. Photoelectric type weft sensor as claimed in claim 4 wherein said light emitter is disposed in said lathe, said light receiver is disposed in the reed cap of the loom, said light receiver includes a cavitated casing and said weft image selector mechanism includes a lid disposed to the light receptive side end of said casing and having two windows, one of which is positioned on the side of the lid toward the reeds of the loom and the other of which is positioned on the cloth fell side of said lid.

24. Photoelectric type weft sensor as claimed in claim 23 wherein said discrimination circuit includes a discriminator connected to a photoelectric cell of said one window, a differential rectifier circuit connected to said discriminator via an integration circuit and a discriminator, a discriminator connected to a photoelectric cell of said cloth fell side window an inverter circuit connected to this discriminator, a gate circuit connected to this inverter circuit and to said first mentioned discriminator, a flip-flop circuit connected to this gate circuit and to said differential rectifier circuit a differential rectifier circuit connected to said second mentioned discriminator, an AND circuit connected to this differential rectifier circuit and said flip-flop circuit and said operation terminal connected to this AND circuit.

25. Photoelectric type weft sensor as claimed in claim 4 wherein said light emitter is disposed in the reed cap of the loom, said light receiver is disposed in

said lathe, said light receiver includes a cavitated casing and said weft-image selector mechanism includes a lid disposed to the light receptive side end of said casing and having two windows, one of which is positioned on the side of the lid toward the reeds of the loom and the other of which is positioned on the cloth fell side of said lid.

26. Photoelectric type weft sensor as claimed in claim 25 wherein said discrimination circuit includes a discriminator connected to a photoelectric cell of said one window, a differential rectifier circuit connected to said discriminator via an integration circuit and a discriminator, a discriminator connected to a photoelectric cell of said cloth fell side window an inverter circuit connected to this discriminator, a gate circuit connected to this inverter circuit and to said first mentioned discriminator, a flip-flop circuit connected to this gate circuit and to said differential rectifier circuit a differential rectifier circuit connected to said second mentioned discriminator, an AND circuit connected to said differential rectifier circuit and said flip-flop circuit, and said operation terminal connected to this AND circuit.

27. Photoelectric type weft sensor as claimed in claim 4 wherein said light emitter includes a cylindrical casing fixed to a part of the loom, a convex lens disposed at the light emitting end of said casing, a cap inserted over said casing on the other side and a lamp carried by said cap with its filament being registered at the weft direction.

28. Photoelectric type weft sensor as claimed in claim 4 wherein said light emitter is fixed to the reed cap and said light receiver is movably mounted in a recess of the lathe.

29. Photoelectric type weft sensor as claimed in claim 28 wherein said light receiver is accompanied by an actuating mechanism and said light receiver moves forwardly out of said recess and rearwardly into said recess being actuated by the swing movement of the lathe via said actuating mechanism which includes a fixed cam and a cam follower roller connected to said light receiver.

30. Photoelectric type weft sensor as claimed in claim 28 wherein said light receiver is accompanied by an actuating mechanism and said light receiver moves forwardly out of said recess and rearwardly into said recess being actuated by the rotation of the tappet shaft via said actuating mechanism which includes an actuator cam, a slider and its related assembly accompanying said light receiver and a transmission mechanism between said cam and said assembly.
